United States Patent Office

Des. 221,838

Patented Sept. 14, 1971

221,838

PACKAGING CUP

Robert A. Fraser, Baltimore, Md., assignor to
J. H. Filbert, Inc., Baltimore, Md.

Filed May 28, 1970, Ser. No. 23,199

Term of patent 14 years

Int. Cl. D9—04

U.S. Cl. D9—220

FIG. 1

FIG. 2

FIG. 3

FIG. 1 is a side elevational view of a packaging cup showing my new design;

FIG. 2 is a top plan view thereof; and

FIG. 3 is an enlarged sectional view through the rim portion of the cup shown in FIG. 1.

The decorative band is continuous about the periphery of the cup as shown in FIG. 1.

I claim:

The ornamental design for a packaging cup, as shown and described.
